POWER-OPERATED HAND TOOL

Edward H. Karleen, Denville, N. J., assignor to
Processing Equipment Corporation, Bloomfield,
N. J., a corporation of New York

Application February 12, 1949, Serial No. 76,118

8 Claims. (Cl. 74—57)

1

This invention relates to a power operated hand tool normally employed in drilling and sawing operations.

The object of this invention is to provide in such a hand tool both rotary and reciprocating motion and means for quickly and readily converting from one form of motion to the other.

Another object is to permit such mechanism to be incorporated in a compact housing that may be conveniently held and used in the hands of the operator.

A still further object is to permit of easy access to the operating parts of the mechanism.

A further object is to produce a well balanced, relatively quiet operating hand tool with all of its actuating parts protectively housed.

Other objects will appear from the description which follows.

This invention is described in the accompanying drawing in which

Figure 1 is a side elevational view of a unit embodying this invention.

Figure 2 is an enlarged side elevational section of the unit shown in Figure 1 complete with drill chuck.

Figure 3 is a top view of the motion controlling parts of the unit shown positioned to provide reciprocating motion.

Figure 4 is a section through 4—4 of Figure 3.

Figure 5 is an enlargement of section 5—5 of Figure 3.

Figure 6 is similar to Figure 3 showing the motion controlling parts positioned to provide rotary motion.

Referring to the drawings in which the same or similar numbers refer to the same or similar parts, the tool is housed in body 1 which follows the general outline of a pistol, having hand grip 2 and switch trigger 5 which enhance the pistol like appearance of the body.

Electric conductors 3 are brought into hand grip 2 to connect with switch 4 which may be closed by squeezing switch trigger 5. To hold the switch trigger in switch closed position, trigger lock 6 projecting through the butt of hand grip 2 is available and upon being pressed inward holds switch trigger 5 in locked engagement.

Motor 7 is centrally housed and is journaled in bearings 10. Brush holders 8 are positioned to be accessible from the exterior of body 1 to permit ease in replacing worn out brushes. Upon rotor shaft 9 is mounted fan 11 to air cool motor 7. Louvres 13 and slots 12 in body 1 provide air intake and exhaust openings.

2

The rotary motion produced by rotor shaft 9 is communicated through intermediate cluster gear 14 to gear 21' which is integral with gear sleeve 21 which in turn encircles and is secured to rotating sleeve 20 by pins 22.

Through rotating sleeve 20 passes shaft 15 which bears drill chuck 16 at its outer end. Rotating sleeve 20 is journaled in bearings 10 and at all times when switch 4 is closed revolves under the action of motor 7. A circumferential cam slot is cut into the interior surface of rotating sleeve 20 and in rolling contact in such cam slot is cam roller 18 mounted on roller stud 17 which projects radially outward from shaft 15 as best shown in Figure 4. Rotating sleeve 20 at one end terminates in clutch teeth 23 adapted to engage with opposite cooperating teeth 23 on linking sleeve 25.

Linking sleeve 25 is splined to shaft 15 as best shown in Figure 5, with splines 24, and is axially movable thereon. As best shown in Figures 3 and 6, at one end it has teeth 23 and at the other end teeth 26. Teeth 26 are engageable with stationary brake 27 which is immovably secured to body 1. In the side of linking sleeve 25, as shown best in Figure 5, slot 28 accommodates the operating end of clutch lever 29. Clutch lever 29 is mounted in the side of body 1 on eccentric 30 so that when clutch lever 29 is moved through 180° by means of clutch lever knob 31, linking sleeve 25 will be moved out of engagement with stationary brake 27 and into engagement with rotating sleeve 20. To define the terminal ends of this 180° range of clutch lever 29, detents 33, as shown in Figure 1, are provided in body 1 and clutch lever knob ball and spring 32 housed in clutch lever knob 31 cooperate to hold clutch lever 29 in either of the two detents when the clutch lever knob 31 is moved into position over one of them.

The operation of the unit shown and described is as follows. Switch trigger 5 is pressed by the operator and locked in closed position by the operator's pressure upon trigger lock 6. The motor having been thus actuated will cause, through rotor shaft 9 and intermediate cluster gear 14 and gear 21', the rotating sleeve 20 to revolve. Irrespective of the movement to be imparted to shaft 15, this sleeve 20 will at all times revolve as long as the motor 7 turns over. When the linking sleeve 25 is in the position shown in Figure 3, rotating sleeve 20 in revolving will be in rolling engagement with cam roller 18, causing roller stud 17, shaft 15 and drill chuck 16 to be reciprocated, but not rotated.

When it is desired to have rotary motion imparted to drill chuck 16, clutch lever 29 is thrown forward to the position shown in Figure 6, causing linking sleeve 25 to disengage from stationary brake 27 and to engage with rotating sleeve 20. When so engaged rotating sleeve 20 will cause linking sleeve 25 to rotate and, it being splined on shaft 15, it will cause shaft 15 to rotate. When shaft 15 rotates with rotating sleeve 20, roller stud 17 will remain stationary in cam slot 19 and drill chuck 16 will be rotated but not reciprocated.

When clutch lever 29 is thrown to its rearward position, linking sleeve 25 is disengaged from rotating sleeve 20 and engaged with stationary brake 27 thus preventing shaft 15 from rotating but permitting it to reciprocate axially in the direction of splines 24. Roller stud 17 when restrained from rotating about the axis of shaft 15 will once again be given reciprocating motion by the action of cam slot 19 upon it.

It is apparent that many modifications may be made in this invention without departing from the scope thereof and the specific illustrations herein given are not to be construed as limiting such scope.

What I claim is:

1. In a power operated hand tool holder, a drill chuck bearing shaft to which reciprocating motion is imparted by means of a rotating sleeve encircling such shaft and operably connected therewith by a pin projecting radially from such shaft into a circumferential cam slot in the interior surface of such sleeve, said shaft being restrained from rotating by a linking sleeve splined thereto and engaged with a stationary brake; and to which rotary motion is imparted by means holding said linking sleeve in disengagement with said stationary brake and in engagement with the said rotating sleeve.

2. In a power operated hand tool holder, a drill chuck bearing shaft to which reciprocating motion is imparted by means of a rotating sleeve encircling such shaft and operably connected therewith by a pin in one member slideable in a cam slot in the other member, said shaft being restrained from rotating by a linking sleeve splined thereto and engaged with a stationary brake; and to which rotary motion is imparted by means holding said linking sleeve in disengagement with said stationary brake and in engagement with the said rotating sleeve.

3. A power operated hand tool holder comprising an electric motor operably connected with a rotatable sleeve having clutch teeth at one end and a circumferential cam slot in its interior surface; a shaft journaled in such sleeve bearing a drill chuck at one end and provided with splines in the portion adjacent its other end and having a stud projecting into said cam slot; a linking sleeve with clutch teeth at each end splined to said shaft and moveable thereon; and a stationary brake facing said linking sleeve and engageable therewith.

4. A power operated hand tool holder comprising an electric motor operably connected with a rotatable sleeve having clutch teeth at one end and a circumferential cam slot in its interior surface; a shaft journaled in such sleeve bear-

ing a drill chuck at one end and provided with splines in the portion adjacent its other end and having a stud mounted roller projecting into said cam slot; a linking sleeve with clutch teeth at each end splined to said shaft and moveable thereon; and a stationary brake facing said linking sleeve and engageable therewith.

5. A power operated hand tool holder comprising an electric motor operably connected with a rotatable sleeve having clutch teeth at one end and a circumferential cam slot in its interior surface; a shaft journaled in such sleeve bearing a drill chuck at one end and provided with splines in the portion adjacent its other end and having a stud mounted roller projecting into said cam slot; a stationary brake; a linking sleeve with clutch teeth at each end splined to said shaft and moveable in an axial direction thereon; and means for selectively moving the linking sleeve into engagement with said rotating sleeve or with said stationary brake.

6. A power operated hand tool holder comprising an electric motor operably connected with a gear ring encircling and secured to a sleeve having clutch teeth at one end and a circumferential cam slot in its interior surface; a shaft journaled in such sleeve bearing a drill chuck at one end and provided with splines in the portion adjacent its other end and having a stud mounted roller projecting into said cam slot; a stationary brake; a linking sleeve with clutch teeth at each end splined to said shaft and moveable thereon in an axial direction and means for selectively moving the linking sleeve into engagement with said rotating sleeve or with said stationary brake.

7. Means for translating rotary motion to reciprocating motion and vice versa comprising a rotating sleeve with an internal circumferential cam slot and with clutch teeth at one end; a shaft journaled in such sleeve with a pin projecting into such cam slot and provided with splines in one portion thereof; and a linking sleeve splined to said shaft and moveable thereon to selective engagement with either a stationary brake or with the clutch teeth of said rotating sleeve.

8. Means for translating rotary motion to reciprocating motion and vice versa comprising a rotating sleeve with clutch teeth at one end; a shaft journaled in such sleeve and provided with splines in one portion thereof; a cam slot and pin slideable therein operably connecting said shaft and said rotating sleeve; and a linking sleeve splined to said shaft and moveable thereon to selective engagement with either a stationary brake or the clutch teeth of said rotating sleeve.
